INVENTOR:

EDWARD M. SMITH,
BY Graham + Kain

ATTORNEYS.

UNITED STATES PATENT OFFICE.

EDWARD M. SMITH, OF LOS ANGELES, CALIFORNIA.

SAND WHEEL FOR OIL WELLS.

Application filed December 6, 1921. Serial No. 520,251.

To all whom it may concern:

Be it known that I, EDWARD M. SMITH, a citizen of the United States, residing at Los Angeles, in the county of Los Angeles and State of California, have invented a new and useful Sand Wheel for Oil Wells, of which the following is a specification.

My invention relates to oil well drilling and operating equipment, and relates particularly to a sand wheel by which the reel upon which the sand line is wound, is revolved.

In oil well equipment, sand reels upon which the sand line is wound are revolved by bringing a sand wheel into frictional contact with the band of a revolving bull wheel. It is common to construct these sand wheels of wood cants, as wood furnishes greater gripping qualities than metals, but a decided disadvantage exists in the use of wood due to the poor wearing qualities thereof and its low resistance against the high frictional heat to which it is subjected.

It is an object of my invention to provide a sand wheel which will have high resistance to wear, and which will have greater gripping qualities than those now in use.

It is also an object of my invention to provide a sand wheel, the surface of which will not ignite due to the excessive frictional heat caused by the slipping of the sand wheel upon the bull wheel.

It is a further object of my invention to provide a sand wheel having a renewable frictionally engaging peripheral surface which may be quickly and cheaply replaced.

Other objects and advantages will appear hereinafter from the following specification and drawings.

Referring to the drawings, which are for illustrative purposes only,

Fig. 1 is a fragmentary perspective view illustrating the application of sand wheels.

Fig. 2 is a perspective view partially in section illustrating a preferred form of my invention.

Fig. 3 is a fragmentary detail showing several of the friction blocks and a portion of the retaining member illustrated in Fig. 1, disposed in extended relationship.

As shown in Fig. 1 of the drawing, the sand wheel 11, upon which is wound the sand line, has mounted upon the same shaft therewith a sand wheel 12 adapted to be brought into frictional contact with a bull

wheel 14 by actuating a lever 15 in the direction of the arrow 17, the lever 15 being connected to a pivoted arm 18 through a bar 19 so that with the forward movement of the lever 15, a movement in the direction of the arrow 20 is imparted to the arm 18. The wear to which the circumferential surfaces of these sand wheels are subjected is very severe, and the heat generated by the friction between the sand wheel and the bull wheel is sometimes sufficient to ignite splinters of the wood from which the sand wheel and the bull wheel are constructed, which is very dangerous around a producing well owing to the liability of oil igniting.

In the embodiment of my invention shown in Figs. 2 and 3, I employ a pulley 25 which is mounted upon the sand reel shaft 26, this pulley having disposed around the periphery thereof a layer 27 of a material having considerable gripping power and high frictional resistance, such as asbestos. It is preferable to provide this layer 27 in the form of arcuated blocks 28, which may be maintained between the flanges 29 and 30 of a circular channel member 31 placed over the band 33 of the pulley 25, the blocks 28 and the channel member 31 being secured upon the band 33 by bolts 34 which extend through counter-bored holes 35 in the blocks 28 and holes 35 provided in the channel member 31. The outer surface 38 of the blocks 28 is slightly concave, so that a flat surface will not be presented to the bull wheel, thus giving a greater gripping power to the sand wheel. The feature of supplying the layer 27 in the form of friction blocks 28 makes it possible to expediently renew the frictional engaging layer 27 when it has become considerably worn away.

With the use of my invention, the fire hazard due to the sparks caused by the friction between the sand wheel and the bull wheel of an oil well drilling equipment is entirely eliminated. A desired advantage of my invention over the wood sand wheels now in use, resides in the increased gripping power, the high resistance to wear, and the expediency and economy of renewing the friction blocks.

I claim as my invention:

1. In a friction pulley, the combination of: a cylindrical band; a block retainer having a cylindrical bore to fit snugly upon

said band; a plurality of friction blocks fitting over and carried by said retainer; and bolts passing through said blocks, said retainer and said band and locking said retainer and blocks solidly on said band.

2. A combination as specified in claim 1 in which the band retainer is in the form

of a channel with the flanges turned outwardly, said blocks fitting snugly between said flanges.

In testimony whereof, I have hereunto set my hand at Los Angeles, California, this 30th day of November, 1921.

EDWARD M. SMITH.
